WILLIAM P. UHLINGER.

UNITED STATES PATENT OFFICE.

WILLIAM P. UHLINGER, OF PHILADELPHIA, PENNSYLVANIA.

DESIGN FOR A CARRIAGE-BODY.

SPECIFICATION forming part of Design No. 13,001, dated June 20, 1882.

Application filed April 27, 1882. Term of patent 7 years.

To all whom it may concern:

Be it known that I, WILLIAM P. UHLINGER, a citizen of the United States, and a resident of Philadelphia, in the county of Philadelphia and State of Pennsylvania, have invented a new and valuable Improvement in Designs for Carriage-Bodies; and I do hereby declare that the following is a full, clear, and exact description of the construction and operation of the same, reference being had to the annexed photograph, making a part of this specification, and to the letters and figures of reference marked thereon.

This design has relation to the body of a carriage or light wagon; and it consists in the novel form or configuration set forth.

The letter *a* indicates the bottom line of the body, which is horizontal and straight from the dash-front back to the obtuse-angled under recess, *b*, at the end of the body.

The letter *c* represents the top edge of the body-side, which is horizontal and straight from the rear end of the body forward to the obtuse-angled cut-away portion *d* at the front of the body between the front seat and the dash.

Above the straight edge *c* is a rectangular-paneled rail-guard, *e*.

The re-entrant obtuse angles *g* *g'* of the under recess in rear and the cut-away portion in front are similar to each other and to the salient angles *h* and *h'*.

The oblique edges *k* and *k'* of the recess *b*

and cut-away portion *d* are parallel, and the horizontal lines thereof, *l* and *l'*, would, if produced, coincide, or nearly coincide, as indicated in the drawings. The short horizontal edge *l'* in front extends from the foot of the oblique edge *k'* to the dash-front *m*, which is vertical. The short horizontal line *l* of the under recess extends from the top of the oblique edge *k* to the back wall, *n*, which is vertical.

The body may or may not have the uprights *v*, curved top *s*, and brace-rails *z*.

What I claim and desire to secure is—

The design for a carriage-body set forth, wherein the body is formed with a straight horizontal bottom edge, *a*, extending from its vertical front to an obtuse-angled under recess, *b*, at its rear end, a straight horizontal upper edge, *c*, extending from the vertical back *n* to an obtuse-angled cut-away portion, *d*, in front, the parallel oblique edges *k'* *k* and the short horizontal lines *l'* *l* extending respectively in front and rear from said oblique edges to the vertical dash and vertical back, as shown and set forth.

In testimony that I claim the above I have hereunto subscribed my name in the presence of two witnesses.

WILLIAM P. UHLINGER.
